DRAFT GEARS FOR RAILWAY CARS

Herbert E. Tucker, Chicago, Ill., assignor to Cardwell Westinghouse Company, a corporation of Delaware

Application September 7, 1951, Serial No. 245,573

5 Claims. (Cl. 213—45)

This invention relates to draft gears for railway cars, and has for its principal object to provide a relatively soft cushioning unit of short travel and low capacity acting in buff and in draft, and a relatively hard long travel cushioning unit of high capacity also acting in buff only and in series with the relatively soft cushioning unit.

Other objects and advantages of the invention will appear as the description is read in connection with the accompanying drawings, in which:

Fig. 1 is a horizontal section through the draft gear and associated parts;

Figs. 2 and 3 are cross-sections on the lines 2—2 and 3—3 of Fig. 1 respectively;

Fig. 4 is a diagram giving comparative curves of the two cushioning units and a combination of the two; and

Fig. 5 is a perspective view indicating how the resilient elements or spring elements are made up.

In the drawings, 10 and 11 indicate spaced sills equipped with draft lugs 12 and 13 which together define a conventional draft gear pocket. Associated with those parts is a coupler shank 14 and a draft yoke 15 connected to the coupler shank in any suitable way.

The draft gear includes a housing 16 divided by a partition 17 into a generally rectangular rear chamber 18 (Fig. 2) for the low capacity cushioning unit, and a generally hexagonal front chamber 19 (Fig. 3) for the high capacity cushioning unit.

The soft, low capacity or rear cushioning unit is made up of resilient elements or spring elements, generally indicated by 20, alternating with spacers. As shown in Fig. 5, each element is made up of a plate 21 of relatively incompressible material (preferably steel $\frac{3}{16}$ " S. A. E. 1010 is satisfactory) provided with rows of aligned, spaced openings 22, rubber bars or mats 23 overlying the rows of openings on each side of the plate are connected by plugs 24. The bars and plugs are of material such as rubber composition, of suitable durometer hardness, for example 58 to 62. The connection between the bars and the plugs, or one bar and the plugs, is effected by vulcanizing, which may, or may not, also make the bars fast to the steel plates.

In making up the soft, low capacity cushioning unit in this embodiment, three resilient or rubber elements, including plates 21 and rubber blocks 23, alternate with steel spacer plates 25, the group or pack having an overall length in excess of the length of the chamber 18 approximately one inch, thus providing a one-inch soft travel low capacity cushion for buff and draft shocks. In use, it is assembled between the partition 17 and a back follower plate 26.

The high capacity long travel cushioning unit, or front unit, is preferably substantially as disclosed in the patent to Cardwell, 2,496,442 of February 7, 1950. However, in this instance the inner and outer coil springs are shown replaced by a cushioning element composed of five main rubber springs, generally indicated by 27 in Fig. 1, alternating with spacers 28. Each rubber spring is made up of a plate 32 provided on each side with concentric rubber

2

rings 29 connected by blocks 30 through openings 31 formed in the plate 32.

The remainder of the friction draft gear disclosed in the said Cardwell patent is not here described in detail, but the disclosure in that patent is included by reference in the interest of brevity.

The rear follower 26 has a hollow boss 33 which receives the headed end 42 of the bolt 40 which passes through the friction draft gear and serves to retain the units in assembled relation, as shown in Fig. 1.

A front follower 37 is disposed between the coupler shank 14 and the friction cushioning unit and transmits buff loads therebetween. The front follower is limited in its forward travel by abutment with the front draft lugs 13.

In operation, the soft low capacity rubber cushioning unit provides one inch travel in all important draft shocks. The action is soft and easy and has plenty of capacity and travel.

That soft low capacity cushioning unit also provides one inch travel on the rubber in buff. Any light buffing shocks will probably be taken care of mostly by the rubber, though undoubtedly at it reaches the end of its compression the friction will come in play. The two cushioning units acting together provide full three inches of travel in buff, and while light buff shocks are taken principally by the soft low capacity unit there is necessarily a blending, and as the low capacity unit reaches the capacity of limited travel the friction draft gear comes into full play for two inches, or approximately two inches, of capacity.

Generally speaking, the high capacity cushioning unit will be idle until there is a buff shock approaching the capacity or exceeding the capacity of the soft, low cushioning unit. When that occurs, the friction of the high capacity unit will come into play and take care of the shock.

Referring to Fig. 4, the results are graphically shown. The characteristic curve of the Cardwell friction gear shown at 50' approaches a straight line when plotted with inches of travel as abscissa and loads as ordinates. The characteristic curve of the low capacity cushioning unit indicated at 51' is quite a long curve. The combination of the two is indicated by the curve 52 from which it will appear that the draft gear is softer than friction draft gears when considered as a whole, but has the softness of a rubber draft gear for draft shocks or buff shocks within the capacity of the low soft cushioning unit.

Wherever in the specification and claims the terms "hard" and "soft" are employed to describe the cushioning units they should be understood to refer to the cushioning units as a whole and not necessarily to the individual elements thereof. The characteristic load-deflection curve for a relatively hard cushioning unit, of course, shows that for a given increment of load there results only a small deflection, whereas the characteristic load-deflection curve for a relatively soft cushioning unit for a similar increment of load would produce a substantially greater deflection.

I claim:

1. In a draft gear for a railway car having a draft gear pocket, a draft yoke, followers movable by the yoke, and spaced stops against which the followers normally rest, a housing mounted in the draft pocket for longitudinal movement therein between one of said stops and one of said followers, said housing normally occupying a position with one end thereof abutting said one stop and the opposite end thereof spaced from said one follower, a partition wall in said housing dividing it into two chambers, a cushioning unit in one of said chambers between said partition wall and said one follower, said cushioning unit including a series of rubber blocks alternating with relatively incompressible plates, a friction cushioning unit in the other of said chambers between said partition wall

and the other of said followers, said one follower being movable by said draft yoke away from its associated stop to cause said first mentioned cushioning unit to act in draft, said housing, during such movement of said one follower, being held against movement by the stop which it normally abuts, whereby said friction cushioning unit is prevented from acting in draft, said other follower being movable by said draft yoke away from its associated stop to cause both of said cushioning units to cooperatively act in buff.

2. In a draft gear for a railway car having a draft gear pocket, a draft yoke, followers movable by the yoke, and spaced stops against which the followers normally rest, a housing mounted in the draft pocket for longitudinal movement therein between one of said stops and one of said followers, said housing normally occupying a position with one end thereof abutting said one stop and the opposite end thereof spaced from said one follower, a partition wall in said housing dividing it into two chambers of different lengths and cross-sections, a short travel cushioning unit in the shorter chamber between said partition wall and said one follower, said cushioning unit including a series of rubber blocks alternating with relatively incompressible plates, a friction cushioning unit in the second chamber between said partition wall and the other of said followers, said short travel cushioning unit being softer than said friction cushioning unit, said one follower being movable by said draft yoke away from its associated stop to cause said first mentioned cushioning unit to act in draft, said housing, during such movement of said one follower, being held against movement by the stop which it normally abuts, whereby said friction cushioning unit is prevented from acting in draft, said other follower being movable by said draft yoke away from its associated stop to cause both of said cushioning units to cooperatively act in buff.

3. In a draft gear for mounting in a draft gear pocket of a railway car, said pocket having front and rear stop lugs, and adapted to be actuated by a coupler yoke encircling the gear, a housing mounted in the pocket for longitudinal movement therein, a partition wall in said housing dividing it into two chambers of different lengths, a rear cushioning unit in the chamber of shorter length and having one end abutting said partition wall, a rear follower abutting the opposite end of said cushioning unit, said rear follower and housing having cooperating portions for limiting relative movement of said follower toward said partition wall, and said portions being in longitudinally spaced relation whereby said follower may move toward said partition wall to cause said cushioning unit

to act in draft, a front cushioning unit in the chambers of greater length and having one end thereof abutting said partition wall, a front follower abutting the opposite end of said front cushioning unit, said front follower and said housing being movable toward said rear follower to cause both of said cushioning units to act in buff, said housing normally abutting against said front stops to prevent movement thereof when the gear is acting in draft whereby said front cushioning unit is prevented from acting in draft.

4. The invention recited in claim 3, wherein said rear cushioning unit is softer than said front cushioning unit.

5. In a draft gear for mounting in a draft gear pocket of a railway car, said pocket having front and rear stop lugs, and adapted to be actuated by a coupler yoke encircling the gear, a housing mounted in the pocket for longitudinal movement therein, a partition wall in said housing dividing it into front and rear chambers, a rear cushioning unit in said rear chamber having one end thereof abutting said partition wall, a rear follower abutting the opposite end of said cushioning unit, said follower and housing having cooperating portions for limiting relative movement of said rear follower toward said partition wall and said portions normally being in longitudinally spaced relation whereby said follower may move toward said partition wall to cause said rear cushioning unit to act in draft, a front cushioning unit in said front chamber having one end abutting said partition wall, and a front follower abutting the opposite end of said front cushioning unit, said front follower and said housing being movable toward said rear follower to cause both of said cushioning units to act in buff, said housing normally abutting against said front stops to prevent movement thereof when the gear is acting in draft whereby said front cushioning unit is prevented from acting in draft.
